ERNST PETERSSON, OF OREBRO, SWEDEN

FURNACE FOR CASTING IRON AND OTHER DIFFICULT FUSIBLE METALS UNDER
PRESSURE

Application filed November 5, 1926, Serial No. 146,449, and in Sweden January 9, 1925.

This invention relates to furnaces for casting iron and other difficult fusible metals under pressure, particularly when producing the pressure by vacuum, in which there is provided, between the molten metal in the furnace or in a crucible located in the furnace and an opening made in the wall of the furnace, a casting pipe consisting of fire-proof material and having a nozzle against which a mold is adapted to be pressed at the casting instant.

The object of the invention is, for one thing, to prevent cooling and solidifying of the molten metal, before it reaches the mold, and for the other to effect a vacuum-tight connection between the molten metal in the furnace or in the crucible, respectively, and the mold.

The invention consists essentially in this that the casting nozzle is located within the furnace at a place, where it is exposed to the furnace heat, so as to prevent solidifying of the molten metal, the surface of the said nozzle, against which the mold is adapted to be pressed, having such a shape and the casting pipe carrying the nozzle being adjustably connected to the body of the furnace in such a manner that when the said surface of the nozzle is pressed against a correspondingly shaped surface of the mold, the said surfaces will automatically adjust themselves with relation to each other, so that an air-tight connection will be obtained between the nozzle and the mold. The said surfaces may preferably be plane, and the casting pipe may be hinged to the furnace body by means of a self-adjusting suspension device permitting of a free adjustment of the pipe in all directions.

In the annexed drawing one form of embodiment of an arrangement according to the invention is shown. Fig. 1 is a vertical section through a melting furnace having a device according to the invention. Fig. 2 is a partial sectional end view showing the suspension device for the casting pipe.

In the drawing, 1 designates the melting furnace which may be heated in electrical way or in any other known manner and in which there is placed a crucible 2 for the metal. Ar-

ranged in the wall of the furnace at a suitable height above the rim of the crucible is a preferably circular opening 3, the outer extended part 4 of which is provided with a metal lining 5 forming right before the opening 3 a sleeve 6 fitting closely to the opening 3.

Placed in the crucible 2 is an angularly bent casting pipe 7 consisting of fire-proof material and extending about to the bottom of the crucible and at the upper free end of which there is rigidly secured a cup 8 consisting also of fire-proof material. Inserted in the bottom of the said cup 8 is a nozzle 9 having the shape of a circular plate, the fore free side of which is plane-ground and located so far within the furnace that the temperature at the opening of the nozzle lies above the temperature of solidification of the metal. The casting pipe 7 and the nozzle 9 may be connected to the cup 8 by means of fire-lute. The cup 8 is surrounded at its fore open end by a ring 10 consisting preferably of steel and is pivotally connected to said ring by means of two diametrically opposite gudgeons 11 screwed into the ring 10. The ring 10 is in turn pivotally connected to the stationary sleeve 6 by means of two likewise diametrically opposite gudgeons 12 screwed into the sleeve 6 and lying in an axial plane forming right angles with the axial plane containing the gudgeon 11, so that there will be formed a Cardan suspension device for the cup 8 with the nozzle 9 and the casting pipe 7. The nozzle 9 will consequently, upon pressing the plane-ground fore end of the mold 13 against it, automatically adjust itself with its plane-ground end in an exact alignment with the plane end of the mold, so that an air-tight connection will be obtained between the mold and the nozzle.

The opening 14 of the nozzle 9, which communicates with the casting pipe 7 through a channel 15 in the bottom of the cup 8, is, as apparent from Fig. 1, preferably conical and inclined, so that, when the mold 13 is removed and the vacuum ceases, the molten metal can easily flow back to the crucible 2.

The desired self-adjustment of the casting pipe with the nozzle, resulting in a tight connection between the latter and the mold, may

evidently also be effected for instance by this that the casting pipe or the cup 8 connected thereto is made exteriorly spherical and applied in a spherical seat in the wall of the 5 furnace.

What I claim is:—

1. In a device for casting iron and other difficultly fusible metals by forcing the molten metal into the mold by means of a vacuum, 10 the combination of a furnace having an opening in its wall, a casting pipe located between the molten metal in the furnace and said opening in the furnace wall and made of fire-proof material, a nozzle on the outer end of said pipe against which the mold is adapted to be pressed in the casting operation, and a self-adjusting suspension device carrying said pipe and the nozzle, said nozzle being located within the furnace at a place where it is exposed to the furnace heat, the surface of the nozzle adapted to be pressed against the mold having such a shape that, when pressing it against a correspondingly shaped surface of the mold, the said surfaces will, due to said 20 self-adjusting suspension device, automatically adjust themselves with relation to each other, so as to perform an air-tight connection between the nozzle and the mold.
2. In a device for casting iron and other difficultly fusible metals by forcing the molten metal into the mold by means of a vacuum, the combination of a furnace having an opening in its wall, a casting pipe located between the molten metal in the furnace and said opening 30 in the furnace wall and made of fire-proof material, a nozzle on the outer end of said pipe against which the mold is adapted to be pressed at the casting operation, and a self-adjusting suspension device carrying said pipe and the nozzle, said nozzle being located within the furnace at a place where it is exposed to the furnace heat, a surface of the nozzle adapted to be pressed against the mold having such a shape that, when pressing it 40 against a correspondingly shaped surface of the mold, the said surfaces will, due to said self-adjusting suspension device, automatically adjust themselves with relation to each other, so as to perform an air-tight connection between the nozzle and the mold.
3. In a device for casting iron and other difficultly fusible metals by forcing the molten metal into the mold by vacuum, the combination of a furnace having an opening in its wall, a casting pipe located between the molten metal in the furnace and said opening 45 in the furnace wall and made of fire-proof material, a nozzle on the outer end of said pipe against which the mold is adapted to be pressed at the casting operation, and a self-adjusting suspension device carrying said pipe and the nozzle, said nozzle being located at the bottom of said cup-shaped part.
4. In a device according to claim 3, characterized by the channel of the nozzle being conical. 50 In testimony whereof I affix my signature.

ERNST PETERSSON.

within the furnace at a place where it is exposed to the furnace heat, a surface of the nozzle adapted to be pressed against the mold having such a shape that, when pressing it against a correspondingly shaped surface of the mold, the said surfaces will, due to said self-adjusting suspension device, automatically adjust themselves with relation to each other, so as to perform an air-tight connection between the nozzle and the mold, the channel of the nozzle taking up an inclined position and having the outlet located at the top.

4. A device according to claim 3, characterized by the channel of the nozzle being conical. 80
